(57) **CLAIM**

The ornamental design for a tire, as shown and described.

DESCRIPTION

FIG. 1 is a perspective view of a tire showing my new design; FIG. 2 is a front view thereof;

FIG. 3 is a rear view thereof;

FIG. 4 is a top plan view thereof, for which the bottom plan view is the same;

FIG. 5 is a right side view thereof;

FIG. 6 is a left side view thereof;

FIG. 7 is a cross-sectional view taken along line 7-7 in FIG. 2 and line 7'-7' in FIG. 5; and,

FIG. 8 is a cross-sectional view taken along line 8-8 in FIG. 2 and line 7-7' in FIG. 5.

In the drawings, the broken lines defining portions of the tire tread, sidewall and inner bead depict environmental subject matter that forms no part of the claimed design.
